UNITED STATES PATENT OFFICE.

ARRAH J. WHISLER, OF KOKOMO, INDIANA.

DESIGN FOR A TIRE-REPAIRING PLUG.

SPECIFICATION forming part of Design No. 29,268, dated August 23, 1898.

Application filed August 2, 1898. Serial No. 687,567. Term of patent 8½ years.

To all whom it may concern:

Be it known that I, ARRAH J. WHISLER, a citizen of the United States, residing at Kokomo, in the county of Howard and State of Indiana, have invented and produced a new and original Design for Tire-Repairing Plugs, of which the following is a specification, reference being had to the accompanying drawings, forming part thereof, and in which—
10 Figure 1 is a perspective view, and Fig. 2 is a longitudinal sectional view, of a plug, showing my new design.

The leading or material feature of my design consists of the design forming the subject-matter of the accompanying illustration, wherein my plug is illustrated in perspective and longitudinal section.

As shown, the plug-stem A is provided at its lower end with the upwardly-flaring rim 15 B, whose outer side tapers at its lower end to

a point at C. This rim B extends upwardly to a point about on a level with the upper end of the stem A, the space within the rim B being conical, as will be understood from Fig. 2, and extending from the lower end of the 25 stem A to about the level of the upper end of such stem.

Incidentally the stem A is provided with a central opening D, extending downward toward the lower end of such stem. 30

Having described my invention, what I claim as new, and desire to secure by Letters Patent, is—

The design for a tire-repairing plug, as herein shown and described.

ARRAH J. WHISLER.
